UNITED STATES PATENT OFFICE.

WALTER C. MOORS, OF OWENSBORO, KENTUCKY.

CLOTHES-DRYING RACK.

Application filed February 14, 1924. Serial No. 692,816.

To all whom it may concern:

Be it known that I, WALTER C. MOORS, a citizen of the United States, residing at Owensboro, in the county of Daviess and State of Kentucky, have invented certain new and useful Improvements in Clothes-Drying Racks, of which the following is a specification, reference being had therein to the accompanying drawing.

10 The present invention relates to clothes drying racks, and aims to provide a novel and improved construction of that kind.

15 A more specific object of the invention is the provision of such a rack having a post with means for securing it firmly in place between and clamped against the floor and ceiling of a room.

20 Another object is the provision of novel rack members movably mounted on the post to be conveniently positioned for placing the clothes thereon and removing the clothes therefrom, and including radial arms or bars adapted to be folded adjacent to the post when not in use.

25 A further object is the provision of novel means for adjustably supporting the rack members on the post, and for conveniently enabling the rack members to be raised and lowered and to be supported at different vertical positions.

30 It is also an object of the invention to provide such a rack structure which is comparatively simple and inexpensive in construction, which will have a comparatively large capacity while requiring comparatively little space within the room, and which can be compactly folded to be stored away when not in use.

35 With the foregoing and other objects in view, which will be apparent as the description proceeds, the invention resides in the construction and arrangement of parts, as hereinafter described and claimed, it being understood that changes can be made within 40 the scope of what is claimed, without departing from the spirit of the invention.

The invention is illustrated in the accompanying drawings, wherein:—

45 Figure 1 is a side elevation of the rack, portions being broken away.

50 Figs. 2, 3, 4 and 5 are enlarged horizontal sections on the respective lines 2—2, 3—3, 4—4, and 5—5 of Fig. 1.

Fig. 6 is a vertical section on the line 6—6 of Fig. 2, portions being broken away. 55

Fig. 7 is an elevation of the pole or rod used for raising and lowering the rack members, showing the socket tube in section.

Fig. 8 is a perspective view of the rack showing a modified form of stand. 60

Fig. 9 is a detail view of the modified form of stand, partly in elevation, and partly in section, showing the same fitted over a stake as when using the rack out-of-doors. 65

Fig. 10 is a detail view of the upper end portion of the stand and clamp, portions being broken away and shown in section.

Fig. 11 is a cross section on the line 11—11 of Fig. 10. 70

In carrying out the invention, there is provided a post 10 which is adjustable vertically for rooms of different heights, and the lower portion of the post is fitted slidably in a stand comprising the base 11 and a pair of spaced bars 12 having their lower ends secured in the base. The post is slidable between the bars 12, and transverse guide pieces 13 are secured to opposite sides of the lower terminal of the post and overlap the edges of the bars 12 to guide the lower terminal of the post in the stand for vertical adjustment. 75

The post 10, base 11 and bars 12 may be of wood or other suitable material, and a head 16 of similar material is fitted loosely on the reduced upper end portion 14 of the post. The head 16 is of inverted conical form, having a central aperture receiving the post, and having a flared rim to contact with the ceiling surrounding the upper end of the post. A washer 15 is secured on the upper end of the post by a screw 15' or other securing element, for retaining the head on the post, and a coiled wire spring 17 surrounds the portion 14 and is confined between the head 16 and the shoulder 17^a of the post. 90

In order to clamp the post 10 in different vertical positions relatively to the stand, the stand is formed with a clamp at its upper end to embrace the post. The upper terminals of the bars 12 form part of the clamp, said bars being adapted to be sprung toward one another to clamp the post between them. Plates 18 extend across the edges of the bars 100

12 and opposite sides of the post 10, and are secured, by means of screws 19 or otherwise, to the upper terminal of one bar 12. The plates 18 may be connected by a yoke 20 so as to constitute a single band of U-shape, thereby adding strength to the structure. Screws 21 or other elements are secured in the other bar 12 and work in slots 22 provided in the plates 18, and a cam 23 is pivotally mounted between the plates 18 on a bolt or pin 23^a extending through said plates and cam to contact with the bar that is slideable between the plates 18. Said cam has a handle or lever 24. When the lever 24 is swung downwardly the cam 23 forces the corresponding bar 12 toward the opposite bar, as seen in Fig. 6, thereby clamping the post 10 between said bars and maintaining the adjustment of the rack. When the lever 24 is swung upwardly, the post 10 is loosened so that it can be moved vertically in the stand.

In order to position the device in a room, the post and stand are slid together, whereby the device can be readily placed at the desired position on the floor. The base 11 is set on the floor, and the post 10 is then raised to bring the head 16 against the ceiling and to compress the spring 17. The head 16 being fitted loosely on the upper terminal portion 14 of the post, can tilt relatively to the post, so as to bear flatly against the ceiling, should the surface of the ceiling not be level or should the post be slightly inclined from a vertical position. The lever 24 is swung downwardly to clamp the post 10 within the stand, and the spring 17 being compressed will hold the base 11 and head 16 against the floor and ceiling, respectively, under pressure to prevent the device from being displaced or knocked down. The spring 17 thus separates the base and head with sufficient pressure to hold them tightly against the floor and ceiling. To loosen the post, the lever 24 is simply swung upwardly which permits the post 10 to slide down into the stand, to reduce the height of the rack, so that it can be removed or taken down.

Two rack members or frames are mounted on the post, as shown, although any number of them can be used as may be found suitable under different circumstances. Each rack member or frame comprises a set of radial arms or bars 25 extending in different directions in a horizontal plane from a hub 26 which is slideable and rotatable on the post. The hub 26 has pairs of radial vertical flanges or bracket arms 28 projecting therefrom, and said flanges or arms 28 are connected at their outer ends and lower edges by the cross bars or pieces 27 over which the arms 25 extend. The hub 26 has a flat annular flange 29 above the inner ends of the flanges 28 under which the inner ends of the arms 25 extend. Staples or U-shaped

keepers 32 have their ends driven or secured within the arms 25 at the lower edges thereof around the cross bars 27, for retaining the arms 25 in operative connection with the hub member, said keepers 32 being of sufficient size to enable the arms 25 to be slid longitudinally a limited distance and to be swung upwardly and downwardly. 70

When the arms 25 are in operative position they are in a horizontal plane with their inner ends extending under and bearing upwardly against the flange 29, and with the arms seating on the cross bars 27, the arms being slid inwardly to engage under said flange 29. By sliding the arms outwardly 80 they are withdrawn from under the flange 29, and the arms can then swing downwardly to folded or collapsed position, as indicated in dotted lines in Fig. 6, the keepers 32 serving to loosely suspend the arms. The arms 25 can thus be arranged close to the post when the rack is not in use. To bring the arms in position for supporting the clothes or other articles, the arms are swung upwardly to horizontal position and then 90 slid inwardly to move the inner ends of the arms under the flange 29. The keepers 32 thus connect the arms with the hub member for the longitudinal sliding and vertical swinging movements of said arms. 95

Each rack member or frame is adjustably supported on the post to be disposed at different vertical positions conveniently, and to permit the rack member to rotate in any of its vertical positions. Thus, a supporting 100 sleeve 36 is slidably mounted on the post under each hub 26, and the hub seats on the upper end of said sleeve. The sleeve is split diametrically, and the two sections thereof are secured together by means of clamping 105 bolts or screws 37. The adjacent ends of the hub 26 and sleeve 36 have a swivel connection whereby they move one with the other, and the hub 26 can rotate while the sleeve 36 is secured in position on the post. Thus, 110 the lower end of the hub 26 has an outstanding annular flange 38, and the upper end of the sleeve 36 has an annular groove portion 39 embracing and engaging over the flange 38. The portion 39 can be readily engaged 115 over the flange 38 when the sections of the sleeve 36 are brought together.

Each sleeve 36 carries means for clamping it to the post. Thus, the sleeve has outstanding portions 41 at the adjacent edges of the sections of the sleeve at one side, and said portions 41 have a recess 40 between them in which a dog 42 is disposed. The dog 42 is mounted for vertical turning movement on a pivot 43 extending transversely through the portions 41, and the dog projects toward the post and is so formed as to bind between the pivot 43 and post under the weight of the rack member or frame. A coiled spring 44 is confined between the dog 42 and the 120

125

130

bottom of the recess 40 to swing the dog into engagement with the post, whereby the dog, when released, will cause the sleeve 36 to bind on or grip the post for supporting the rack member or frame.

The dog 42 of each sleeve 36 is provided at its outer end with a depending finger 45, and a catch 46 is pivoted, as at 47, to the portions 41 of the sleeve 36 and normally 10 swings downwardly by gravity. The finger 45 has a notch 48 for the engagement of the catch 46, when the finger 45 is swung away from the post so as to move the dog 42 to releasing position. When the catch is engaged in the notch 48, the dog is held in released position, thereby permitting the sleeve 36 and hub 26 to move upwardly and downwardly on the post freely.

A pole or rod 49 is used for conveniently 20 raising and lowering the rack members. A tube 50 is fitted on the upper end of said pole or stick 49, and provides a socket to receive the finger 45 of the dog 42. Said pole is of sufficient length in order to raise 25 the upper rack member to the upper end of the post. When using the pole 49, the tube or socket member 50 is moved upwardly into engagement with the finger 45 of the corresponding dog 42, and the lower end of the 30 pole is then swung away from the post, which will swing the dog 42 downwardly out of engagement with the post. The rack member can then be conveniently raised or lowered with the pole 49, and when the pole 35 49 is swung inwardly the dog 42 is returned into engagement with the post, for supporting the rack member in its adjusted position.

When filling a rack member with clothes, it is moved to a lowered position, and the 40 upper rack member is first filled. Then, the rack member is slid upwardly by simply pushing it upward, and will be supported in its raised position by the dog 42. The next rack can then be filled and slid upwardly to 45 a position below the clothes on the upper rack member. Although the pole or stick 49 can be used for pushing the rack members upwardly, they can be raised in any suitable manner, inasmuch as the dogs 42 can drag 50 along the post when the rack members are raised. However, the dogs must be released to enable the rack members to be lowered, so that the pole or stick 49 is used for letting the rack members move down.

55 When it is desired to lower the rack members, the tube or socket member 50 of the pole 49 is engaged with the finger 45, and the pole is swung outwardly away from the post, to release the dog 42, and the rack member can then be readily lowered with the pole. The lowermost rack member is first lowered and the clothes removed therefrom, after which the upper rack member is lowered and emptied.

60 65 When the rack is not in use, the arms 25

can be swung downwardly adjacent to the post, so that the rack will not consume much space, and the rack, when loosened from the ceiling, can be taken down and stored away within small space.

The rack can also be used in the corner of a room by placing the post at the corner of the room after those arms 25 adjacent to the walls of the room have been swung downwardly, so that only the remaining arms are available for supporting the clothes. This arrangement is satisfactory when the full capacity of the rack is not required.

Figs. 8, 9, 10 and 11 illustrate a different 80 stand for the post 10, said post and rack members carried thereby being the same as hereinbefore described. The stand comprises a hollow conical base 11' and a vertical tube 12' having its lower end portion 85 secured in the apex of the base by means of rivets or other securing elements, and the lower terminal of the post is fitted telescopically within the tube, to permit the post to be raised and lowered.

The upper end portion of the tube 12' has a clamp to embrace the post for supporting the post from the stand in different 90 adjustments. Thus, a collar or band 18' 95 embraces the upper end portion of the tube 12' and is secured to said tube in any suitable manner. The collar has the outstanding ears 20' through which a rivet or other pivot element 19' is engaged, and a cam 23' is mounted for turning movement on 100 said pivot between the ears. Said cam has a lever or handle 24' for convenience in turning the cam, and that portion of the tube between the cam and post is free to be sprung inwardly. Thus, the tube 12' has 105 slots 22' extending downwardly from the upper end of the tube, and located at opposite sides of the cam 23', thereby forming an upwardly extending resilient tongue 21' 110 fitting the post and located between the post and cam. When the lever 24' is swung downwardly, the cam 23' bears against the tongue 21' and forces said tongue inwardly, to clamp the post between the tongue and the opposite side of the tube. The tongue 21' is free from the band or collar 18' so 115 that said tongue can be sprung inwardly, and said tongue has a broad bearing surface to contact with the post, to provide an effective clamping action.

In each form of stand, the stand is hollow to telescopically receive the post, and the upper end of the stand carries a cam, while the stand is provided at its upper end with an upwardly extending resilient portion between the post and cam to be sprung toward the opposite side of the stand by the cam to clamp the post.

120 125 130 By using the tubular or hollow stand, the lower end of which is open, the rack can be

used out-of-doors. Thus, as shown in Fig. 9, a stake 70 can be driven in the ground, and the tube 12' can be fitted over said stake to hold the rack in upright position, the base 11' being seatable on the ground. In this way, the rack can be conveniently used outside as well as in the house.

The present invention is an improvement over the clothes drying rack disclosed in my application filed April 23, 1923, Serial No. 634,022, and this application is in part a continuation of such application.

Having thus described the invention, what is claimed as new is:—

15. 1. A rack comprising a base to bear on the floor of a room, a post supported by the base, a head loosely mounted on the upper terminal of the post and having a rim surrounding the upper end of the post to bear upwardly against the ceiling of the room, a rack member supported by said post, a spring surrounding the post and confined between said head and post for

yieldingly moving the head upwardly on the post to clamp the base and head against the floor and ceiling, respectively, and a member on the upper terminal of the post within said rim to limit the upward movement of said head on the post.

2. A rack comprising a post, a sleeve slideable on the post, a rack member carried by the sleeve, a dog pivotally carried by the sleeve to engage the post for clamping the sleeve to the post and having a depending finger to be swung away from the post for disengaging the dog from the post, said finger having a notch, and a catch pivotally carried by the sleeve to be swung upwardly into engagement with said notch for holding the dog disengaged from the post, said catch swinging downward away from said finger when the finger is swung further away from the post.

In testimony whereof I hereunto affix my signature.

WALTER C. MOORS.
